UNITED STATES PATENT OFFICE.

KARL VÖLLER, OF DUSSELDORF, GERMANY, ASSIGNOR TO RHEINISCHE METALLWAAREN- UND MASCHINENFABRIK, OF DUSSELDORF- DERENDORF, GERMANY, A CORPORATION OF GERMANY.

DEVICE FOR PREVENTING THE BARRELS OF DIFFERENTIAL-RECOIL GUNS FROM TILTING IN THE FIRING POSITION.

1,032,869.

Specification of Letters Patent. Patented July 16, 1912.

Application filed August 1, 1911. Serial No. 641,795.

To all whom it may concern:

Be it known that I, KARL VÖLLER, engineer, a subject of the German Emperor, residing at 12 Scharnhorststrasse, Dusseldorf, 5 Germany, have invented certain new and useful Improvements in Devices for Preventing the Barrels of Differential-Recoil Guns from Tilting in the Firing Position; and I do hereby declare the following to be 10 a full, clear, and exact description of the invention, such as will enable others skilled in the art to which it appertains to make and use the same.

In guns with recoiling barrels in which the 15 gun is fired in a stationary position, any play in the elevating gears has little or no effect upon the accuracy of aim, since the projectile has been discharged, when the recoil is set up. In so-called differential recoil guns however, in which the discharge of the projectile occurs toward the end of the forward movement, a tilt may be given to those parts, the barrel and cradle, which are pivoted about the trunnions, by the displacement of their center of gravity on the forward movement, if there is any play in the elevating gear. The projectile is deviated according to the amount of this play and the efficiency of the gun impaired. This disadvantage is obviated according to the present invention by a device which prevents the tilting motion by automatically connecting the pivoted parts, the cradle and barrel, with the fixed carriage at the commencement of 30 the forward sliding movement and releases them at the end of the recoil movement. The connection can be made by a double armed lever journaled in the cradle or cradle support, one arm of which engages in a 35 guiding groove on the gun barrel, while the other arm engages in a part fixed to the carriage. At the beginning of the forward sliding movement the lever turns so as to effect the engagement with the carriage. At 40 the end of the sliding movement the engagement is released. As soon as the coupling is established, the elevating gear is free from strain since the coupling occurs during the sliding movement of the barrel, 45 the action of the elevating gear in the stationary position of the gun is not interfered with.

The accompanying drawings show three constructional forms of the invention.

Figure 1 is a side view of one construction, Fig. 2 is a cross section at the line 2-2 of Fig. 1. Fig. 3 is a cross section at the line 3-3 of Fig. 1. Fig. 4 is a side view and Fig. 5 an end view partly in section of a modified construction. Fig. 6 is a side view and Fig. 7 a section at the line 7-7 of Fig. 6 of another modification.

In Figs. 1-3 *a* is the lower part of the carriage on which the upper part *b* can turn in a horizontal plane. The cradle support *c* is journaled on the upper part *b* so as to turn about the trunnions *d*. The cradle support *c* is rigidly fixed to the cradle *e*, which carries the guides for the barrel *f*. Two toothed sectors *g*, with which the pins *h* of the elevating gear engage, are attached to the cradle. The center of the curves of the toothed sectors lies in the axis of the trunnions. At the side of the cradle support there is a pin *i*, on which a two-armed coupling lever *k* is pivoted. A pin *l* at one end of the lever engages in a guiding groove *m* on the barrel *f*. The other end of the lever *k* forms a coupling with a part *n* fixed to the carriage. A groove wedge-shaped in cross section is formed in the sector shaped part *n*, into which the correspondingly wedge shaped end of the lever *k* loosely fits in the stationary position of the barrel. The guiding groove in the barrel 85 consists of two parts. As soon as the pin *l* reaches the upper part of the groove in the forward movement of the barrel, the lever *k* is turned about its pivot and its wedge shaped end pressed firmly into the wedge 90 shaped groove. Any tilting of the barrel and cradle is thus prevented. At the end of the recoil movement the connection is released. The center of the curve of the wedge shaped groove is in the axis of the 95 trunnion, and the length of the grooves such, that for all practical elevations the coupling is maintained throughout the sliding movement of the barrel.

In the construction shown in Figs. 4 and 100 5 similar parts are denoted with the same reference characters. It differs from the former construction only in the method in which the coupling lever is guided. Two

rollers *o* fixed to the barrel, lie on either side of the bent coupling lever *k*. As soon as the sliding movement of the barrel has brought these rollers on to the higher part 5 of the bent lever *k*, the wedge shaped end of the latter is pressed into the groove. When the rollers are on the lower part of the lever *k*, the wedge shaped end of the lever is raised from the groove and the coupling is again 10 released.

In the construction represented in Figs. 6 and 7 an arm *p*, whose end lies between two cheeks *q*, *q'*, is mounted on the carriage *a*. The contact surfaces of the cheeks are adapted 15 to grip the arm *p*. The cheeks lie in a casing *r* mounted on the cradle *e* and are manipulated by a right and left hand threaded bolt *s* which can be turned by a forked lever *t* attached to the bolt. The lever *t* is partially turned during the forward and backward movements of the barrel by a stop *u* on the latter. This tightens or releases the gripping surfaces of the cheeks *q*, *q'* on the arm *p*. In this way the connection 20 between the movable and fixed parts is first established and afterward released during the to and fro movement of the barrel of the gun.

I claim as my invention:

30 1. In a gun having a differential recoil, the combination of a carriage, a recoiling barrel, means for elevating the barrel, means for automatically locking the barrel to the carriage independently of the elevating mechanism and means for automatically actuating said last mentioned means to effect such locking during the forward movement of the barrel, said last mentioned means automatically releasing said locking mechanism during the recoil of the barrel.

40 2. In a gun having a differential recoil, the combination of a carriage, a recoiling barrel, a cradle therefor, elevating mechanism for the barrel, a movable member on

the cradle, a part fixed on the carriage with 45 which the movable member is designed to bind, and means carried by the barrel for operating said movable member to cause it to bind against said fixed part during the forward movement of the barrel and to release 50 said movable member from said fixed part after firing and during the recoil of the barrel.

3. In a gun having a differential recoil, the combination of a carriage, a recoiling 55 barrel, a cradle therefor, elevating mechanism for the barrel, a lever fulcrumed on the cradle, a part fixed to the carriage against which one end of the lever is designed to bind, and means carried by the 60 barrel for operating said lever to cause it to bind against said fixed part during the forward movement of the barrel and to release 65 said lever from said fixed part after firing and during the recoil of the barrel. 65

4. In a gun having a differential recoil, the combination of a carriage, a recoiling barrel, a cradle therefor, elevating mechanism for the barrel, a lever fulcrumed on the cradle, a part fixed to the carriage 70 against which one end of the lever is designed to bind, and a two-part groove carried by the barrel, the parts of the groove being on different planes, one part of said groove acting on said lever during the forward movement of the barrel to cause it to bind against said fixed part, and the other part of the groove during the recoil of the barrel acting on said lever to release it from 75 said fixed part. 80

In testimony whereof, I have signed this specification in the presence of two subscribing witnesses.
